AUTOMOBILE TORPEDO.

1,351,526.

Specification of Letters Patent. Patented Aug. 31, 1920.

Application filed June 6, 1919. Serial No. 302,367.

To all whom it may concern:

Be it known that we, EDGAR LEES and HERBERT WHEATLEY RIDSDALE, both subjects of the King of Great Britain, residing at 5 Portland Harbour Torpedo Works, Weymouth, in the county of Dorset, England, have invented certain new and useful Improvements in or Relating to Automobile Torpedoes, of which the following is a specification.

This invention relates to automobile torpedoes of the kind in which means are employed for causing the torpedo at a predetermined point in its travel to depart from 10 its initial run (which is herein referred to as "straight" although in practice it is slightly sinuous) and then to steer a curved or other course, the object being again to direct the torpedo toward the target in order that it may have another chance of hitting, should a direct hit not have been effected.

According to the present invention, means are provided for causing relative movement 15 to occur between the controlling valve and the valve seating, the said means being so constructed and arranged in relation to the gyroscope, that this relative movement can be obtained without disturbing the setting 20 of the gyroscope. For this purpose the said means may either cause the valve seating to be moved while the valve remains held by the gyroscope or the said means may cause a device on the vertical (which is usually 25 the outer) gimbal of the gyroscope to operate upon the valve actuating member of this gimbal in such manner as to displace the said member upon the gimbal in the horizontal plane and thereby move the valve 30 relatively to the position in which it would otherwise be held by the gyroscope. The 35 said means preferably embody a series of controlling cams any selected one of which can be moved into an operative position 40 prior to launching, these cams lying dormant until the torpedo has run a predetermined distance after launching; for this 45 purpose an adjustable contrivance, which can be set in accordance with the estimated 50 range of the target, is provided for causing the operation of the cam from the propelling engine to commence as soon as this range has been run. The said controlling 55 cams determine the points of time at which

mechanism for moving the valve or its seat- 55 ing shall come into operation.

The cams may be designed to impart any desired course to the torpedo, but we prefer so to construct them that each will give to the torpedo a spiral course so defined with 60 regard to the speed ratio between the torpedo and the target, that whatever the course in a straight line steered by the target may be, the torpedo and target will eventually meet. The spiral course in question is that already known in naval circles as the "curve of search" and consists in a spiral which cuts each possible radial course of the target steered from a given point of departure, at a point where the time taken 70 by the target to reach that point is equal to the time taken by the torpedo to reach the same point at a higher speed on a course steered along the spiral drawn through all such points on all possible radial lines. The 75 difficulty in applying this curve to a torpedo attack is that the point of departure of the target nearly coincides at the moment of a miss with the point of departure of the torpedo when the miss occurs. The cams 80 are therefore so shaped as to cause the torpedo, should it miss the target, to follow a preliminary or preparatory course before entering the curve of search, this preliminary course, which may be of any desired 85 shape, being of such a length that the time taken by the torpedo in traveling along it is equal to the time required by the target to reach, in a straight line, the point at which the preliminary course terminates. 90 This preliminary course preferably includes a certain amount of "over run" which forms a continuation of the initial straight run of the torpedo and which is introduced to insure that the torpedo shall not depart from 95 its straight run until the target has been passed. Such premature departure would of course make a direct hit impossible if the range had been under-estimated. The curve 100 of search is preferably composed of a number of short straight lines corresponding to the periods when the cam is not causing relative movement to occur between the valve and the valve seating and a number 105 of arcs to which the straight lines are tangents and which correspond to the periods when the cam is operating to cause relative movement to take place between the valve

and the valve seating. Means capable of adjustment prior to the launching of the torpedo, may be provided for enabling the relative movement between the controlling 5 valve and the valve seating to be such as to cause the torpedo to depart from its straight course either to the right or to the left as desired, dependent upon whether the course of the target is to the left or to the right of 10 the line of bearing of the target.

In order that the said invention may be clearly understood and readily carried into effect, we will describe the same more fully with reference to the accompanying drawings in which:—

Fig. 1 shows more or less diagrammatically a side elevation of that form of the invention in which the seating of the controlling valve is moved while the valve 20 mains held by the gyroscope.

Fig. 1^a is a diagrammatic side elevation of a detail hereinafter referred to.

Fig. 2 shows more or less diagrammatically a sectional elevation of a series of the 25 aforesaid cams and the means for moving any selected one of them into an operative position prior to launching.

Fig. 2^a is a plan showing more or less diagrammatically a form of interconnecting 30 mechanism hereinafter referred to.

Fig. 3 shows more or less diagrammatically an end elevation of that form of the invention in which the valve is moved relatively to the position in which it would 35 otherwise be held by the gyroscope.

Fig. 4 is a diagram showing the aforesaid preliminary course and part of the curve of search course steered by the torpedo provided with either of the above forms of the 40 invention, assuming the speed ratio between the torpedo and the target to be five to one. This diagram is marked to indicate in yards the length of the straight portions of the course and in degrees the angular measure 45 of the curved portions of the course, all these curved portions having a common radius of two hundred and sixty yards which is assumed for the purpose of this example to be the minimum turning radius 50 of the torpedo. The spiral portion of the course actually followed by the torpedo is shown by full lines and departs only slightly from the geometrical spiral which is shown by chain lines.

Fig. 5 shows more or less diagrammatically an end elevation similar to Fig. 3 in which an automatic reversing arrangement is provided for causing the torpedo to take a sinuous course, and

Fig. 6 is a section taken approximately on the line 6, 6 of Fig. 5.

A represents the gyroscope comprising as is well understood a flywheel a , an inner gimbal a' and an outer gimbal a'' to which 60 the inner gimbal is connected by horizontal

centers a'' , a'' and which is connected by vertical centers a'' , a'' to a frame A'. B is the rotary controlling valve of usual design, and b' is the valve seating which, in the examples shown, is constituted by a valve 70 cone fitting in an airtight manner in a casing B' forming part of the frame A'; this casing has ports leading to a cylinder containing a relay piston valve the movement of which admits air under pressure to the 75 steering engine which holds the steering rudder hard over alternately to port and starboard as is well understood, the rudder during the run of the torpedo never being held by the steering engine in the central 80 or in a neutral position. The valve cone b' has the usual three circumferential grooves which now serve to maintain communication between the ports in the valve cone and those in the casing B' whatever 85 the angular position of the valve cone may be in relation to the casing. The said valve carries a toothed wheel B² meshing with a similar wheel A² connected to the outer gimbal a'' coaxially with the vertical centers 90 a'' , a'' these toothed wheels taking the place of the usual forked lever connected to the valve and the usual pin on the outer gimbal.

In the form of the invention shown by Fig. 1 the valve cone b' is adapted to be angularly displaced relatively to the valve B and the casing B' when the torpedo is to take a curved path, by the engagement of a pawl C, constantly driven from the propelling engine by an eccentric C' with a 100 ratchet wheel c; this ratchet wheel is connected by pinions c', c'', c''' with a worm C² gearing with a worm wheel C³ connected to or made integral with the valve cone b'.

D represents one of the aforesaid cams the 105 function of which is to control, through a two armed lever d, d', a spring stop or plunger D' and a mask or guard D'', the points of time at which the pawl C shall be allowed to impart movement to the ratchet 110 wheel c and thence to the valve cone b' or the periods during which it shall be prevented from imparting such movement; the rotative position of the cam thus determines whether the torpedo shall take a curved or 115 a straight path. The said cam lies dormant in the position shown until the torpedo has run a predetermined distance after launching with the mask D'' in the masking position shown, preventing the pawl C from imparting movement to the ratchet wheel c. The aforesaid adjustable contrivance for 120 causing the cam to be driven from the propelling engine at the termination of this dormant period, comprises a sleeve E adapted to be angularly set by a shaft E' through the gearing shown in accordance with the estimated range of the target. This sleeve carries a projection e, the circumferential distance of which from a detent arm f cor- 125

responds to the target range setting and which, by the engagement therewith of this 5 detent arm, causes the cam to be driven from the eccentric C' in the manner herein- after described.

The parts are shown as being in the position they occupy when the torpedo has just been launched, with a projection or raised portion d³ of the cam in contact with the 10 arm d of the two-armed lever d, d' and with the sleeve E set to bring the projection e thereon at the required circumferential distance from the detent arm f corresponding to the estimated range of the target. This 15 detent arm engages with a detent g on a ring G and is pivoted at f' to a disk F which is displaced step by step from the propelling engine in the direction of the arrow on this disk through suitable reducing gearing de- 20 riving its motion from a ratchet wheel F'. During the straight run of the torpedo before the detent arm f is disengaged from the detent g by the said arm coming against the projection e, the said ratchet wheel is oper- 25 ated in the direction of the arrow on this wheel by a double pawl f². This double pawl is pivotally carried by a toothed sector F² meshing with another sector F³ to which oscillatory motion is imparted from 30 the engine by the eccentric C' during the whole run of the torpedo. The disk F meshes with a toothed ring F^x carrying a pawl f^x which is adapted to drive the cam D through a ratchet ring F^{xx} (connected to the cam) when the ring F^x is moved in a clockwise direction, but which when the ring F^x is moving in the direction of the arrow on this ring (this being the case when the 35 torpedo is running its straight course be- fore the detent arm f is raised) slips over the teeth of the ratchet ring F^{xx} and the cam is therefore not driven. A restraining pawl f^{xx} is provided for engaging with other ratchet teeth on the ring F^{xx} so as to prevent 40 the cam from moving in an anti-clockwise direction during the time that the pawl f^x is slipping over the teeth on the ratchet ring F^{xx}. These conditions last during the time 45 that the detent arm f is being gradually brought toward and into contact with the projection e and corresponds to the straight run of the torpedo for a distance equal to the estimated range of the target. During 50 this time the eccentric C' is moving the pawl C which is endeavoring to displace the ratchet wheel c appertaining to the valve cone b' but which is prevented from so doing by the mask D² being held in its mask- 55 ing position by the engagement of the plunger D' with the radial face of an arm d² on the said mask.

The ring G is controlled by a spring G' which may be energized by hand prior to the launching of the torpedo or which may 60 be energized automatically at the moment of

launching the torpedo. The means for effecting the energization automatically are shown by Fig. 1^a in which 200 represents the shell of the torpedo, and 201 the usual air lever by means of which the engine start- 70 ing valve is opened as the torpedo leaves the launching tube. 202 is the pivot of this lever and at a short distance from it is a pin 203 which projects from the side of the lever 201 and is connected by a rod 204 to a simi- 75 lar pin at the extremity of an arm 205 pivoted at 206. The arm 205 is made integral with a toe 207 which is adapted to engage an extension 208 of the arm g' on the ring G when in the position in which the 80 spring G' is not engaged. When the lever 201 is drawn back in the act of launching the torpedo, the rod 204 pulls the arm 205 and the toe 207 into the position shown by full lines, the toe engaging with the exten- 85 sion 208 and thereby energizing the spring.

When the detent arm f is moved out of engagement with the detent g as aforesaid at the termination of the straight run of the 90 torpedo over a distance equal to the estimated range of the target, the ring G formed with this detent is caused by the spring G' (which was as aforesaid energized by hand prior to, or automatically at the moment of, the launching of the tor- 95 pedo) to move smartly in the opposite direc- 100 tion until arrested by the engagement of the arm g' thereon with a stop g² on the disk F and to carry with it a sleeve H by means of ratchet teeth on the ring G engaging with a pawl h carried by the sleeve H. This movement of the sleeve is then augmented by a spring H' attached to a pin h² on a toothed disk H² connected to a toothed seg- 105 ment H³ on the sleeve as shown, the pur- 110 pose of this additional movement being to bring the head h^x of the pawl h out of engagement with the ratchet teeth on the ring G and cause it to rest upon a fixed projec- 115 tion H^x carried by the fixed frame A'. The said movement of the sleeve H displaces the anchorage f^{2x} of a spring F^{2x} operating on the double pawl f² into the position shown by chain lines, with the result that the other end of the pawl will now engage 120 with the ratchet wheel F'. In consequence of this, since the sector F² on which the pawl f² is mounted is being continuously oscillated from the engine, the ratchet wheel F' will be moved by the said pawl in the reverse direction to that indicated by the arrow and the rings F, F^x will also in conse- 125 quence move in the reverse directions to those indicated by the arrows thereon. The pawl f^x carried by the latter ring will then commence to move the cam D through the aforesaid gearing from the eccentric C' in the direction shown by the arrow on the cam. The latter continues to move without 130 its altering the position of the plunger D'

through the lever d , d' so long as the projection d^3 of the cam is in contact with the arm d , this period corresponding to the aforesaid over-run of the torpedo; this 5 over-run is represented by the line 1, 2 in Fig. 4 in which 3 indicates the target traveling for example along a straight course represented by the arrow 4, and the arrow 5 indicates the direction of the straight run 10 or direction of attack of the torpedo. When a depression d^4 of the cam comes opposite the arm d a spring D^x operating upon a second plunger d'^x against which the arm d' bears and which contains another spring d^0 15 operating between the two plungers, serves to raise the plunger D' clear of the arm d^2 of the mask D^2 and a spring d'^x then revolves this mask into a position in which a gap therein exposes the teeth of the ratchet 20 wheel c to the action of the pawl C . The latter thus displaces the valve cone b' through the pinions c' , c^2 , c^3 , the worm C^2 and worm wheel C^3 , thereby causing the 25 torpedo to move in the arc of a circle having a radius corresponding to the minimum turning radius of the torpedo. This arcuate movement continues so long as the plunger D' remains in its retracted position, that is to say so long as the depression d^4 of the 30 cam remains opposite the arm d ; this depression corresponds to the travel of the torpedo from the point 2 to the point 2^a of Fig. 4. When this travel has been completed, a second projection d^5 engages the 35 arm d and causes the plunger D' to be depressed so as to protrude into the path of the arm d^2 . During the time that the depression d^4 was opposite the arm d and the plunger D' was in consequence in its retracted position, projections c^x on the ratchet wheel c had been coming into contact (once in every five steps for example of the said wheel) with an arm C^x of a toothed segment C^x gearing with teeth on the mask D^2 40 and had thus been intermittently displacing the mask into a position in which it was about to mask the teeth of the ratchet wheel c ; when each projection moved clear of the arm C^x , which it did at the completion of each series of five steps of the ratchet wheel, the spring d'^x had returned the mask to its 45 normal position since the plunger D^2 was not free to assume or did not occupy its protruding position. When however, a projection in the cam is opposite the arm d , the plunger D' is free to assume or is in its protruding position and the said plunger then engages with the radial face of the arm d^2 as shown at the completion of one of the 50 said series of five steps and thus holds the mask in its masking position as shown. The pawl C is then prevented from actuating the ratchet wheel c and the valve cone b' is therefore no longer operated. The 55 torpedo consequently follows a straight course

during the time that the arm d is in contact with the projection d^5 of the cam, this time corresponding to the travel of the torpedo from the point 2^a to the point 2^b in Fig. 4. At the point 2^b the torpedo enters the 70 curve of search course which is composed of a number of arcs of circles whose lengths correspond to the lengths of the various depressions on the cam D and a number of tangents whose lengths correspond to the lengths of the 75 various projections on the cam. The course from the point 1 to the point 2^b represents the aforesaid preliminary course of the torpedo and is so chosen, having regard to the speed ratio of the torpedo and target, that 80 the time taken for the torpedo, traveling along the said course, to reach the point 2^b equals the time taken by the target to travel in a straight line from the point 1 to the point 2^b had such been its course instead of 85 that shown by the arrow 4. The direction and distance $1-2^b$ is obtained by mathematical computation when each cam is designed. The algebraic law of the spiral is known and the point 2^b in the spiral where 90 the radius of curvature is equivalent to the least turning radius of the torpedo may therefore be determined; this gives the length of the radius $1, 2^b$. Five times this distance (if the speed ratio is five to one) 95 gives the length of the preliminary course from 1 to 2^b , the over-run from 1 to 2 being arbitrarily selected. The remainder of the course is determined algebraically.

In the arrangement shown by Fig. 2 the 100 means for moving any selected one of the aforesaid cams into an operative position prior to launching, comprises a shaft J actuated from the exterior of the torpedo and operating through bevel gearing upon a 105 shaft J' . The latter is rotatably mounted in part of the frame A' and carries a screw J^2 engaging with screw threads formed in a nut j^2 which is prevented from rotating by the engagement of a key j^2x with a slot in the 110 aforesaid part of the frame A' . This nut carries between suitable abutments thereon a sleeve J^3 having pins j^3 , j^3 which pass through a slot j^3x formed in a tubular extension of the aforesaid ratchet ring F^{xx} ; these 115 pins engage with a second sleeve J^4 slidably mounted on the tubular extension and carrying a number of the aforesaid cams. It will thus be seen that by rotating the shaft J any one of the cams can be brought opposite 120 the arm d of the aforesaid two-armed lever d, d' .

The shafts E' and J may be interconnected in such manner that when the latter has first been actuated to bring the cam having 125 the required speed ratio into the operative position, the shaft E' can then be operated to set the projection e only within certain predetermined limits of range dependent on the speed ratio of that particular cam, and 130

when the shaft E' has first been actuated the shaft J can then be actuated to bring into operation only certain of the cams dependent upon the position to which the projection e has been set. The purpose of this interconnection is to prevent the torpedo from returning to the immediate vicinity of the vessel or station from which it was launched. A further purpose is to impose such a speed ratio as shall cover as extensive a useful zone as possible. A constructional form of the interconnecting mechanism is shown in Fig. 2^a in which the shaft J is formed near the shell of the torpedo with a pinion 100 adapted to mesh with a gear wheel 101 made integral with a bush 102. This bush is rotatable about a shaft 103 and carries an indicating finger 104 arranged to be brought opposite any one of markings "Open range" 2, 3, 4, 5, 6 and 7, etc., on the exterior of the shell to show which of the cams D has been brought into the operative position. Integral with the bush 102 is a cam 106 the periphery of which is stepped, equally or unequally as may be desired, and angularly disposed relatively to the indicating finger in such manner as to bring an appropriate step in the periphery of the cam into the path of a movable rack 107, thereby forming for the latter an adjustable stop. This rack is mounted in a guide 108 and may be caused radially to approach or recede from the center of the shaft 103 by means of a pinion 109 with which it gears. This pinion is formed on the shaft E' , and meshes with a gear wheel 110 having a pointer 111 adapted to move over suitable range markings 112 on the exterior of the shell to show the position of the aforesaid projection e of Fig. 1 as set in accordance with the estimated range of the target. The motion of the rack 107 is limited in a direction toward the left by a fixed stop 113 in which position the reading of the pointer 111 is the maximum possible range along which the torpedo may be run, and in a direction toward the right by contact with the periphery of the cam 106 in which position the pointer 111 will indicate the minimum range at which the target may safely be attacked when the particular speed ratio indicated by the finger 104 is being employed. Should it be found desirable just prior to launching the torpedo for example to employ the cam designed for the next higher speed ratio than the one then in the operative position, the shaft J would be adjusted as described thereby bringing the cam 106 into a position in which the step placed in the path of the rack 107 is of smaller radius than the step previously in that position. If thought necessary the target range may now be slightly lessened but only by an amount corresponding to the extra movement toward the right that it is possible to impart to the rack 107. The reason why the

target range may be lessened is that the zone covered by the next higher speed ratio is less extensive than that covered by the next lower ratio. On the other hand should it be desired to lower the speed ratio, the finger 104 could not be adjusted to the required position owing to the engagement of a step in the cam 106 with the back of the rack 107. So therefore to use a lower speed ratio the rack must be withdrawn by increasing the range setting of the pointer 111 by a sufficient amount. Should it be found more convenient to operate the shaft E' in accordance with the estimated range of the target before adjusting the shaft J , then the latter may be adjusted to bring into operation only those cams having the particular speed ratios the minimum target range for which is equal to or less than the range as set. When the lowest step in the periphery of the cam is brought into the path of the rack 107, the selected cam brought into the operative position is a plain one provided (as will be described more in detail hereinafter) for the case of the torpedo being desired to travel in a straight course throughout the whole of its run. In this case the finger 104 will be opposite the marking "Open range" and the range pointer 111 will be capable of adjustment between zero and its maximum range reading.

In order to facilitate the operation of bringing the desired cam into the operative position, we prefer to employ the arrangement shown in Fig. 1 whereby the two-armed lever d, d' is held in a position in which the arm d is not in contact with any of the cams until the torpedo is launched. The said arrangement comprises a spring controlled piston d'' disposed in a cylinder 100 communicating with the compressed air supply for the engine at a point between the starting valve and the engine. The rod of this piston has a notch engaging with a projection b' on the aforesaid two-armed lever 105 so that prior to launching the torpedo (that is to say when there is no air pressure in the cylinder) the spring of the piston will hold the arm d out of contact with the cams. As soon as the starting valve is opened as the 110 torpedo leaves the launching tube, air under pressure is admitted to the cylinder and the piston is moved into the position shown so as to enable the arm d to come into contact with the selected cam. It will be observed that the notch in the end of the piston rod is of sufficient width to enable the projection b' to move freely therein when the two-armed lever is being removed by the cam.

In the form of the invention shown by Fig. 3, the valve cone b' is rigidly connected to the casing B' and the steering of the torpedo in a curved course is effected by moving the controlling valve B relatively to the position in which it would otherwise be held 125 130

by the gyroscope. The aforesaid device for effecting this movement comprises, in the example shown, a rotary air motor K of any suitable construction through which the supply of air employed for maintaining the speed of the flywheel a passes, the air flowing through a channel A'' in the frame A' , an axial hole in the lower vertical center a^{2x} of the outer gimbal a^2 , and a channel a^{xx} in this gimbal to the motor K; from the motor the air passes through ports in a hollow shaft of the motor and along the shaft to a passage a^0 against the surrounding wall of which the end of the shaft abuts, the air then flowing from this passage to a conduit a^x leading to the usual nozzles appertaining to the flywheel. The rotary motor K is connected by gear wheels k, k', k^2, k^3 to a worm K' gearing with a worm wheel K^2 which forms part of or is connected to a gear wheel A^2 meshing with the gear wheel B^2 of the valve B, the gear wheel A^2 constituting the aforesaid valve actuating member of the outer gimbal. The unit comprising the worm wheel K^2 and the gear wheel A^2 is rotatably mounted on the outer gimbal a^2 coaxially with the vertical centers a^{2x}, a^{xx} . The air passing through the motor K is constantly tending to rotate it and the parts driven thereby but is prevented from doing so unless the torpedo is to take a curved path, by the engagement of a pawl L with a notch in a disk k^{3x} , attached concentrically to the gear wheel k^3 , as shown; when the torpedo is to take a curved path, the pawl is moved out of the notch and the motor K then operates to move the valve B from the position in which it would otherwise be held by the gyroscope. The position of the pawl is controlled by the position of the cam D which is similar to the cam of Fig. 1 and is similarly driven from the engine when the torpedo has traveled a distance corresponding to the estimated range of the target; for this purpose the pawl in the example shown forms one arm of a bell-crank lever the other arm L' of which is formed with a toothed quadrant meshing with rack teeth on the rod of a spring controlled piston L^2 . This piston is disposed in a chamber L^3 to which air is admitted from conduits a^{00}, a^{00x} , in the frame A' through a hole in the upper vertical center a^{2x} of the gimbal a^2 , or which is placed to exhaust through the conduit a^{00} and another conduit a^{0x} according to the position of a distributing valve L^4 connected to the arm d' of a two armed lever d, d' whose other arm is adapted to be operated upon by the cam D. When the arm d is in contact with projections on the cam the parts are in the position shown with the pawl L in engagement with the notch in the disk k^{3x} attached to the gear wheel k^3 and the motor K therefore prevented from operating; when however depressions of the cam

are opposite the arm d the pawl assumes its inoperative position and the motor is then allowed to operate to move the valve B and thereby cause the torpedo to take a curved path for so long as the pawl remains in that position. The speed of the motor K and the proportions of the gearing between it and the valve are so chosen that the rate of angular displacement of the valve is somewhat greater than the rate of change in direction of the torpedo's course. Instead of the air motor K a spiral spring operating on clockwork may be employed.

The means for setting the mechanism prior to launching so that the torpedo shall depart from its straight course to the right or to the left as required, may comprise a suitable system of reversing gearing which in the form of the invention shown by Fig. 1 would preferably be interposed between the ratchet wheel c and the worm C^2 and in the form shown by Fig. 3 between the gear wheels k and k^3 .

In the examples shown by Figs. 1 and 3 it has been assumed that when the apparatus has been set to cause the torpedo to be deflected either to the right or to the left of its initial straight course, the curved portions of the subsequent course shall always be in the same direction as the direction of the first deflection. It may be, however, that a course of a sinuous nature is required, that is to say, the torpedo may be required to take a course in which it is caused to steer to the right and to the left alternately. Fig. 5 shows an arrangement applied to the construction shown by Fig. 3 in which an automatic reversing arrangement is employed for obtaining such a course. In this arrangement each of the aforesaid cams D is associated with a second cam M (herein referred to as the reversing cam) the function of which is at predetermined intervals to cause the movement given to the controlling valve B by the motor K to be reversed, the periods of the said intervals being so arranged in relation to the movement of the controlling cam that the reversing device is not permitted to operate while movement is being imparted to the valve as aforesaid, that is to say this operation is allowed to occur only while the gearing interposed between the motor K and the gear wheel A^2 is not in motion. To effect the said reversal there is provided in the example shown a spring-controlled bell-crank lever m, m' whose arm m cooperates with the reversing cam M and whose arm m' is connected to a reversing valve M^2 . When the arm m lies opposite a depression in the reversing cam M the valve M^2 is moved to the left by the spring of the lever m, m' and air under pressure passes through the conduits shown to a cylinder N containing a spring controlled piston n carrying a pivoted spring

controlled rod n' having saw teeth engaging with similar teeth on a wheel n^2 connected by gear wheels n^x, n^{xx} to an eccentric N^2 . Movement of this eccentric serves to displace the 5 reversing gear N^3 which may be any known or suitable type and which is interposed between a shaft n^3 , driven from the gear wheel k^3 , and the worm K' that gears with the worm wheel K^2 mounted on the outer gimbal a^2 . The movement of the reversing gear M^2 to the left as aforesaid also admits air under pressure to a cavity m^3 communicating with a cylinder in which is disposed a cut-off valve M^3 controlled by a 10 spring which normally holds this valve in the open position shown. When air is admitted as stated to the cavity m^3 the cut-off valve is moved to the right and serves to cut off the cylinder n from the source of 15 supply and also to place this cylinder to exhaust through the conduit m^4 , the spring of the piston n then returning the latter to the position shown without imparting movement to the wheel n^2 owing to the shape of the 20 teeth on this wheel and those on the rod n' . A similar operation to that described above occurs each time a depression in the reversing cam M comes opposite the arm m and the points of time at which the reversal of movement of the controlling valve B shall take place is thus determined by the peripheral positions of the said depressions, the raised portions of the cam between the depressions merely serving to return the reversing valve 25 30 M^2 to the position shown and allowing the spring of the cut-off valve M^3 to return it to the open position shown. The stroke of the piston n is so chosen that one complete downward stroke imparts half a revolution to the 35 eccentric N^2 .

In order resiliently to hold the eccentric in either of its two extreme positions, a spring N^0 is connected to a pin n^0 on a pinion n^{00} gearing with the aforesaid pinion n^x to which 40 motion is imparted by the piston n and which transmits movement through the pinion n^{xx} to the eccentric N^2 in a ratio of one to two. The said spring also serves the purpose of preventing the possibility of a number 45 of small vibrations of the piston n becoming cumulative and thus unintentionally effecting reversal of the controlling valve B , since after each such vibration the spring N^0 returns the eccentric to the position it is 50 to occupy for the time being.

A piston M^x similar to the piston d^x is provided for holding the arm m out of contact with the reversing cam until the torpedo is launched.

Although in most cases each of the cams D will be associated with a reversing cam M , this would not be so in the case in which one or more of the cams D is intended to give the torpedo a course with the curved 60 portions in one direction only as, for ex-

ample, that shown by Fig. 4; in this event the controlling cam designed to impart this course would be associated with a plain disk moving in contact with the arm m and serving to hold the reversing valve M^2 in 70 the position shown during the whole time that the said controlling cam is in operation.

The eccentric N^2 can be operated by hand from the exterior of the torpedo by suitable mechanism such as is shown in Fig. 6 75 so as to determine whether the initial departure from the straight course shall be to the right or to the left and consequently to determine the directions of the subsequent turns of the torpedo under the influence of 80 the cam D . For this purpose the said mechanism comprises a shaft N^4 leading to the exterior of the torpedo and connected by the bevel gearing shown with a shaft n^4 which is capable of revolution in one 85 direction only, that is to say in the same direction as the eccentric N^2 . The said shaft is arranged co-axially with the shaft carrying the pinion n^{xx} and has a spring controlled piston N^5 slidably keyed to it and 90 disposed in a cylinder n^5 in the frame A' , to which cylinder air is admitted through the conduit n^6 when the starting valve is opened on launching. The piston N^5 has an extension N^{5x} provided with a lateral projection n^{5x} which, prior to launching when the piston is in its outermost position, is adapted to engage with a lateral projection 95 n^{2x} on the eccentric N^2 (unless this projection already occupies its other extreme position) so that by rotating the shaft N^4 the eccentric can be moved to either of its extreme positions and be resiliently held therein by the spring N^0 as aforesaid thereby bringing the reversing gear N^3 to the 100 required position. When the torpedo is launched air under pressure is admitted to the cylinder n^5 and the piston N^5 is thus caused to assume the position shown in Fig. 6 in which the projection n^{5x} lies out of the 110 path of the projection n^{2x} during the time that the gyroscope is free to turn about the vertical centers a^{2x}, a^{5x} .

Although the aforesaid automatic reversing arrangement has been shown in conjunction with the form of the invention shown by Fig. 3, it could equally well be employed in conjunction with the form of the invention shown by Fig. 1, the reversing gear N^3 then forming part of or taking the 120 place of the system of reversing gearing interposed between the ratchet wheel c and the worm C^2 in Fig. 1.

If desired one of the controlling cams D in any of the examples shown can be made 125 plain and of a diameter equal to the diametrical distance between the raised portions of the other of the cams; when the said plain cam is brought opposite the arm d and the torpedo is launched, no relative move- 130

ment will be caused to take place between the controlling valve B and the valve cone b' and the torpedo will thus travel in a straight course throughout the whole of its 5 run.

It is to be understood that the constructional arrangements herein described for carrying out the invention may be varied without departing from the nature of the 10 invention and that the improvements can be employed in conjunction with torpedoes provided with "angle fire" mechanism.

What we claim and desire to secure by Letters Patent of the United States is:—

15 1. An automobile torpedo of the kind set forth, wherein means are provided for causing relative movement to occur between the controlling valve and the valve seating the said means embodying a cam which remains 20 dormant until the torpedo has run a predetermined distance after launching.

2. An automobile torpedo of the kind set forth, provided with mechanism for causing relative movement to occur between the controlling valve and the valve seating without disturbing the setting of the gyroscope and also provided with a cam driven from the propelling engine for determining the points of time at which the said mechanism shall 30 come into operation to effect the said relative movement.

3. An automobile torpedo of the kind set forth, provided with means for causing relative movement to occur between the controlling valve and the valve seating without disturbing the setting of the gyroscope and with an adjustable contrivance which can be set in accordance with the estimated range of the target for causing the operation 40 of the said means from the propelling engine to commence as soon as this range has been run.

4. In an automobile torpedo of the kind set forth, the combination of mechanism for 45 causing relative movement to occur between the controlling valve and the valve seating without disturbing the setting of the gyroscope, a series of cams any selected one of which can be moved into an operative position prior to launching, an adjustable con-

trivance which can be set in accordance with the estimated range of the target for causing the operation of the cam from the propelling engine to commence as soon as this range has been run, and means whereby said 55 cam determines the points of time at which the said mechanism shall come into operation to effect the said relative movement.

5. An automobile torpedo of the kind set forth, provided with means for causing relative movement to occur between the controlling valve and the valve seating without disturbing the setting of the gyroscope, the said means comprising a cam so constructed as to cause the torpedo, after missing the target, to follow a preliminary or preparatory course and then to follow a course in the form of a spiral so defined with regard to the speed ratio between the torpedo and the target, that whatever may 70 be the course in a straight line steered by the target, the torpedo will eventually meet it.

6. An automobile torpedo of the kind set forth, provided with means for causing relative movement to occur between the controlling valve and the valve seating without disturbing the setting of the gyroscope, the said means comprising a cam and means for commencing to drive said cam only after a predetermined range has been run, said 80 cam being so constructed that when it commences to move it will not operate to effect the said relative movement until after the torpedo has run a predetermined distance 85 beyond the predetermined range.

7. An automobile torpedo of the kind set forth, provided with means for causing relative movement to occur between the valve and the valve seating without disturbing the setting of the gyroscope and with means, capable of adjustment prior to the launching of the torpedo, for enabling this relative movement to cause the torpedo to depart from its course either to the right or to the 90 left as required or as many times as required.
